(57) **CLAIM**

The ornamental design for an support for electronic device holder, as shown and described.

DESCRIPTION

FIG. 1 is a front perspective view of a support for electronic device holder;

FIG. 2 is a rear view of the support for electronic device holder shown in FIG. 1;

FIG. 3 is a front view of the support for electronic device holder shown in FIG. 1;

FIG. 4 is a left side view of the support for electronic device holder shown in FIG. 1;

FIG. 5 is a right side view of the support for electronic device holder shown in FIG. 1;

FIG. 6 is a top view of the support for electronic device holder shown in FIG. 1; and,

FIG. 7 is a bottom view of the support for electronic device holder shown in FIG. 1.

The support for electronic device holder is used for supporting a support device specifically adapted to supporting a support structure for a holder of a particular apparatus such as a wireless phone, GPS, a PDA device, a telephone or other equipment in a convenient position on a smooth surface such as a windshield of a motor vehicle.
